UNITED STATES PATENT OFFICE.

SAMUEL R. DODDS, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTROMAGNETIC SWITCH.

1,384,451.

Specification of Letters Patent. Patented July 12, 1921.

Application filed May 20, 1916. Serial No. 98,805.

To all whom it may concern:

Be it known that I, SAMUEL R. DODDS, a citizen of the United States, and a resident of Wilkinsburg, in the county of Allegheny and State of Pennsylvania, have invented a new and useful Improvement in Electromagnetic Switches, of which the following is a specification.

My invention relates to electromagnetic switches and particularly to such switches as are arranged to close only under predetermined conditions.

My invention has for its object to provide a switch of the above-indicated character which embodies a simple and efficient means for preventing the operation of the switch when the current traversing its energizing winding exceeds a predetermined value.

According to the present invention, the movable element of the switch is controlled by an electromagnet comprising a coil in series with the translating device, the circuit of which is controlled by the switch. The circuit of the energizing coil is controlled by a second or auxiliary electromagnetic switch, the energizing coil of which is in series with the coil of the other or main electromagnet. When the current traversing the circuit of the coils exceeds a predetermined value, the auxiliary electromagnetic switch closes a shunt circuit for the main coil, and the main switch cannot close until the current traversing the auxiliary coil falls to a predetermined value.

The details of my invention will be described in connection with the accompanying drawing, in which the single figure is a side view, partially in elevation and partially in section, of a switch constructed in accordance with my invention.

A base member 1, which may be of slate or other suitable insulating material, supports an electromagnet comprising a core member 2 and a coil 3 that is in series with a motor or other translating device, the circuit of which is to be controlled. A closed conductor 4, which may be, for example, a copper ring, is mounted upon the core member 2 for a purpose to be later described.

A movable contact member 5 is carried by an arm 6 that is pivotally supported by a member 7. The movable contact member 5 contacts with a stationary contact member 8 that is secured to the base member 1.

The terminals of the coil 3 are respectively connected to binding posts 9 and 10 which extend through the base member 1. A shunt circuit for the coil 3 is controlled by an electromagnetically operable switch comprising a stationary member 11 that is supported by, and connected to, the binding post 9 and a pivotally mounted movable member 12 that is supported by, and electrically connected to, the binding post 10. The movable switch member 12 is controlled by an electromagnet comprising a coil 13 and a movable core member 14 that is secured to the movable member 12. The value of the current required to effect the engagement of the contact members 11 and 12 may be varied by adjusting the position of a nut 15 on a screw-threaded shaft 16 that is connected to the movable member 12.

It may be assumed that the movable contact member 5 and the arm 6 to which it is connected are in their respective open or inoperative positions. When it is desired to close the switch, the circuit of the coil 3 may be closed in any suitable manner. Current then traverses a circuit comprising conductor 17 which is connected to, and insulated from, the binding post 9, coil 13, contact member 11, binding post 9, coil 3, binding post 10 and conductor 18. If the current traversing the circuit above traced is below the value necessary to effect the engagement of the contact members 11 and 12, the coil 3 is energized to effect the closing of the main switch at its contact members 5 and 8.

If, however, the current exceeds a predetermined value, the coil 13 is energized to effect the engagement of contact members 11 and 12 and thereby close a shunt circuit for the coil 3 by directly connecting the binding posts 10 and 11 which are connected to the terminals of the coil 3.

In case a heavy rush of current follows the closing of the circuit of the coil 3, the main switch is prevented from closing until sufficient time has elapsed to permit the auxiliary switch to close in case the current is above the predetermined value. The closed coil 4 induces flux that is opposed to that induced by the coil 3 and thus delays the operation of the main switch for a period that is sufficient to insure the operation of the auxiliary switch.

I provide a simple means for preventing

- the energization of the coil of an electromagnet for controlling a switch or for de-energizing the coil should the current traversing it exceed a predetermined safe value.
- 5 My invention is particularly adapted for use in connection with starting devices for electric motors in which it is desirable to prevent the shunting of the starting resistor as long as the current traversing the motor 10 circuit exceeds a predetermined value. The switch may be employed, however, in connection with any apparatus in which the above-described method of control may be desirable.
- 15 I claim as my invention:
1. In a switch, the combination with a pair of coacting contact members and an electromagnet comprising a coil for effecting engagement of said contact members, of an electromagnetic switch for preventing the 20 energization of said coil by short-circuiting the same when the current traversing it exceeds a predetermined value.
  2. In a switch, the combination with a pair of coacting contact members and an electromagnet comprising a coil for effecting engagement of said contact members, of an electromagnetically operated switch for shunting said coil when the current traversing it exceeds a predetermined value.
  3. In a switch, the combination with a pair of coacting contact members and an electromagnet comprising a coil for actuating one of the said contact members, of means for de-energizing said coil when the current traversing it exceeds a predetermined value, said means comprising a switch member and an electromagnet having a coil 25 in series with the first-mentioned coil.
4. In a switch, the combination with a pair of coöperating contact members and an electromagnet for effecting engagement of said contact members, of means for effecting the de-energization of said electromagnet after a predetermined current traverses the same, and means for opposing the effect of a sudden change in the value of the current supplied to said electromagnet.
5. In a switch, the combination with co- 40 operating contact members and an electromagnet for effecting engagement of the contact members, of means for so de-energizing the said electromagnet when the current traversing it exceeds a predetermined value that the contact members remain disengaged.
6. In a switch, the combination with co- 45 operating contact members and an electromagnet for actuating the contact members, of means for effecting the de-energization of the said electromagnet when the current traversing the same exceeds a predetermined value, and means for delaying the operation of the electromagnet when the current traversing the same changes suddenly.
7. In a switch, the combination with co- 50 operating contact members and an electromagnet for actuating the contact members, of means for effecting the de-energization of the said electromagnet when the current traversing the same exceeds a predetermined value, and electromagnetic means for delaying the operation of the electromagnet under 55 predetermined conditions.
- 60 In testimony whereof, I have hereunto 65 subscribed my name this 29th day of April 70 75 1916.

SAMUEL R. DODDS.
